UNITED STATES PATENT OFFICE.

EMMA A. MILLER, OF VARINA, IOWA.

WINDOW-PANE-HOLDING DEVICE.

1,065,958.

Specification of Letters Patent.

Patented July 1, 1913.

Application filed October 27, 1910. Serial No. 589,400.

To all whom it may concern:

Be it known that I, EMMA A. MILLER, a citizen of the United States, residing at Varina, in the county of Pocahontas, State 5 of Iowa, have invented certain new and useful Improvements in Window-Pane-Holding Devices; and I do hereby declare the following to be a full, clear, and exact description of the invention, such as will enable others skilled in the art to which it 10 pertains to make and use the same.

This invention relates to improvements in devices for securing window panes in position on sashes without the use of putty and 15 the leading object of the invention is to provide a frame comprising sections adjustably secured together so that different sized panes can be secured to different sized window sashes.

20 With the above and other objects in view the invention consists in certain constructions, combinations and arrangements of parts, clearly described in the following specification and clearly illustrated in the 25 accompanying drawings, in which:—

Figure 1 is a front elevation showing the device applied to a sash for holding a single window pane. Fig. 2 is a detail sectional view taken on the line 2—2 of Fig. 1. Fig. 30 3 is a detail perspective view of an end of one of the frame sections.

35 Referring to the accompanying drawings illustrating the preferred embodiment of the invention 5 denotes a sash comprising vertical members and horizontal members suitably secured together and formed with shoulders 6 against which the window pane 7 is positioned. In the usual method of fastening panes a layer of putty is placed 40 against the edges of the window pane and the inner side faces of the sash members. This method is found to be defective in many respects as putty frequently becomes loose through the jarring of the window sashes, 45 the pressure of wind or other like influences, and the window pane soon vibrates on its sash.

In order to overcome the defects in the 50 common putty method of holding window panes in place, the improved device consists of two frame sections 8 and 9, each section being formed substantially like the other with the exception that one of the sections 9 is formed slightly smaller than the other

section 8 so that the two will slide on one 55 another and each section is provided with two flanges, an inner flange 10, which contacts with a layer of rubber or felt or like material 11 pressed against the edges of the window pane 7, and a second flange 12 which 60 bears against the layer 13 of felt or rubber disposed against the inner sides of the sash member. The frame sections 9 and 10 are also formed with flanges 14 and 15 which are offset at 16 so as to provide tracks 17 for 65 the holding ears 18. The ears 18 are stamped out of the flanges 14 and 15 and are bent around said flanges so as to form depending terminals 19. The flange 14 of the section 10 is adapted to move against the 70 inner side of the flange 15 of the frame section 9.

The frame sections 9 and 10 are secured to the sides of the sash 5 by means of fastening devices or screws 20 whereby the entire 75 frame will be held snugly against the felt or rubber strips and the window pane will be effectively secured against displacement.

The improved window pane holding frame can be manufactured very cheaply and by 80 suitably trimming the rubber strip or felt interposed between the sides of the frame and sides of the sash to which the frame is to be secured the frame can be adapted to practically all sashes. 85

What is claimed is:—

1. A window pane holding device comprising a pair of angular frame sections having their ends bent to slidably engage with the ends of the other section, one flange of 90 each section being off-set adjacent its outer portion so as to space the same inwardly from a window frame, each frame section having its off-set portion adjacent the ends thereof formed with integral ears bent 95 therefrom and adapted to engage the other frame section at the outer edge of its off-set portion, said ears being bent upwardly at right angles to the off-set portion to form a packing seat, and means for holding said 100 sash contacting sides of the angular frame sections in snug engagement with the sides of the sash frame.

2. A window pane holding device including sections of right angular cross section, 105 the ends of said sections being disposed in overlapped relation for adjustment and having certain sides engageable with a window

pane, one side of each section being provided with an offset portion adjacent its outer edge to space the same from the sash frame and the other section having an integral inwardly extending ear bent at right angles to said offset portion for engaging the outer ends of the other sections at their offset portions and forming a retaining means for a

packing engaged in said space provided by the offset portions.

In testimony whereof, I affix my signature, in presence of two witnesses.

EMMA A. MILLER.
